TAP

Frank E. Rice, Detroit, Mich., assignor to American Tap-Bush Company, Detroit, Mich., a corporation of Michigan

Application July 19, 1933, Serial No. 681,052

6 Claims. (Cl. 285—40)

The present invention relates generally to taps and more particularly to taps for beer barrels and the like and to the cooperative construction of the tap and sealing washer for the pump rod whereby easier insertion of the rod is made possible, and the rod is secured in the tap in such manner that excessive pressure within the barrel will not dislodge the rod.

An object of the invention is to provide a tap construction whereby increased pressure within the barrel will increase the gripping effect of the rod holding means to prevent accidental displacement of the rod because of such pressure.

Another object of the invention is to provide a tap for beer barrels so constructed as to increase the extent of washer surface exposed to pressure conditions in a barrel.

Another object of the invention is to provide in a beer barrel tap construction whereby the surface of the pump rod sealing washer exposed to the pressure conditions in the barrel is increased whereby the washer is thus caused to more firmly grip the rod and prevent its accidental displacement due to the pressure conditions in the barrel.

A further object of the invention is to improve taps for beer barrels and the like whereby accidental displacement of the pump rod due to pressure conditions in the barrel is prevented, and a greater sealing effect is secured between the sealing washer and the rod.

The above, other and further objects of the invention will be apparent from the following description, accompanying drawing, and appended claims:

Generally speaking, the invention contemplates the construction of a beer barrel tap and pump rod sealing washer in such manner as to provide increased washer surface for exposure to pressure conditions in the tapped barrel.

Embodiments of the present invention are illustrated in the accompanying drawing, and the views thereof are as follows:

Figure 1 is a view, partially in elevation and partially in vertical section, of a tap constructed in accordance with the principles of the present invention.

Figure 2 is a fragmental, vertical sectional view through a tap constructed in accordance with the present invention showing a beer pump rod in position in the tap, and illustrating another form of the invention.

Figure 3 is a view of the arrangement of Figure 1 showing the pump rod in position in the tap and the washer deformed as the follower is screwed home to secure the rod in the tap.

Figure 4 is a top plan view of a pump sealing washer embodying principles of the present invention.

The drawing will now be explained:

A tap designated generally as A has the usual sleeve 1 for attaching it to a collar 2 which latter is arranged for removable engagement with a tap bush in a keg or barrel D. The tap A has the usual connection 3 for receiving means for supplying pressure to the interior of the barrel through the tap. In the form of tap herein illustrated, the outer end thereof is bored to a greater diameter than the main opening through the tap body. The opening through the tap body is indicated at 3 and the opening in the outer end of the tap at 4. Intermediate the openings 3 and 4 is an annular shoulder 5 having an opening 6 therethrough. The shoulder 5 provides a seat for a sealing washer, designated generally as B. The outer end of the tap A is closed by the usual cap 7 in screw threaded engagement with the exterior of the outer end of the tap, and which cap is provided in its interior with a follower 8 which is adapted to bear against the sealing washer B and after the pump rod has been inserted in the tap the follower bears against the sealing washer B to compress it as the cap is tightened on the tap. Preferably the follower 8 is rotatably arranged in the cap 7.

The shoulder 5 has a face 9 in the form illustrated in Figures 1 and 3, against which the face 10 of the sealing washer B engages when the parts are assembled.

One of these faces is tapered or inclined toward the inner or barrel end of the tap for the purpose of providing means for exposing a larger portion of the face of the sealing washer to the gas pressure within the keg, so that such pressure, instead of tending to dislodge the pump rod C, because of such pressure, will bear against the sealing washer B and because of the increased area of such washer exposed to such pressure, will tighten the engagement of the washer with the rod to increase the holding effect of the washer with respect to the rod and at the same time increase the sealing of the joint about the rod to prevent escape of gas pressure from the keg or barrel.

In the form of the invention illustrated in Figure 1, the sealing washer B has its opposite faces parallel, while the face 9 of the shoulder 5 is tapered or inclined. A washer contacts the adjacent face of the shoulder at the washer margin, as shown in Figures 1 and 3 where it contacts

along the outer margin and in Figure 2 along the inner margin.

In the form of the invention illustrated in Figure 2, the outer face 11 of the shoulder 5' is substantially perpendicular to the axis of the tap, that is, such face is flat or horizontal. The face 12, that is, the adjacent face of the sealing washer B' is tapered or conical shaped and arranged with such tapered face toward the inner 10 or barrel end of the tap. This form of the invention provides a space between the adjacent faces of the sealing washer and shoulder for increasing the area of the sealing washer exposed to pressure within the keg for more firmly sealing 15 the washer about the pump rod C as heretofore described.

Figure 3 illustrates the position of the parts after a pump rod C has been applied through the tap A in the usual manner, and the cap 7 screwed 20 home to tighten the sealing washer B about the pump rod C. It will be observed that the lower face 10 of the sealing washer B has become distorted and assumed a tapered shape. This is caused by the fact that the washer is compressed 25 by the follower 8 as the cap is screwed home, and because of the fact of the pressure exerted by the sealing washer B about the pump rod C as the cap is screwed home. It will thus be observed that the sealing washer B engages the 30 pump rod C with a biting effect which is increased by pressure conditions within the keg or barrel thereby augmenting the gripping effect of the sealing washer B with respect to the rod C, and thus increase the frictional engagement 35 of these parts and prevent accidental dislodgement of the rod due to excessive pressure conditions within the keg or barrel, as oftentimes occur in use.

The same biting effect between the sealing 40 washer and the pump rod C would prevail in the form of the invention illustrated in Figure 2 with the biting effect especially effective adjacent the face 11 of the shoulder 5'.

It will be observed that the present invention 45 contemplates a cooperative construction relationship between the sealing washer and the tap shoulder so that there is provided increased area of the sealing washer exposed to pressure conditions within the keg or barrel, consequently as 50 such pressure increases, the biting effect between the sealing washer and pump rod is increased thereby assuring a tight joint and at the same time preventing accidental dislodgement of the pump rod due to such increased pressure.

55 In the form of the invention as illustrated in Figure 2, the gas pressure in the keg or barrel reaches the face 12 of the washer B' through the aperture in the shoulder 5'.

The invention has been described herein more 60 or less precisely as to details yet it is to be understood that the invention is not limited thereby, as changes may be made in the arrangement and proportion of parts, and equivalents may be substituted, without departing from the spirit 65 and scope of the invention.

The invention is claimed as follows:

1. A beer barrel tap having an internal shoulder 70 providing a seat for a pump rod sealing washer and having an opening therethrough for the pump rod, the diameter of said opening being greater than the diameter of the pump rod, said shoulder having a face, a rod washer having marginal contact with said shoulder, the face of said shoulder adjacent said washer being inclined convergently 75 toward the shoulder opening, the opposite faces of

said washer being parallel, and a follower having a flat surface for engagement with said washer to compress said washer about the pump rod and to deflect the face of the washer adjacent the shoulder out of parallelism with the face engaged by said follower, the space between the rod and shoulder serving to allow fluid passage thereby for increasing the frictional engagement of the washer with the rod to prevent endwise displacement of the rod by gas pressure within the barrel. 85

2. Means for restraining a beer barrel pump rod from endwise displacement from a beer barrel by gas pressure within the barrel, including a pump rod having a smooth outer surface free of projections, a tap applied to said barrel and having a rod receiving chamber and a washer supporting shoulder adjacent the outer end of said chamber and having an opening spaced from said rod, a resilient washer encircling said rod and having only its margin against said shoulder with the adjacent face of the washer spaced from the shoulder face, said washer having a central opening for the rod the surface of which opening is in contact with said rod throughout the whole extent of said surface, means engaging said washer for compressing it lengthwise of the rod to frictionally engage the rod radially thereof, the space between said shoulder and said rod serving as means for admitting gas pressure from the barrel against said washer to increase the squeezing effect of said washer against said rod, the rod being prevented from bodily removal from the barrel by gas pressure within said barrel solely by the frictional engagement of said washer with said rod. 95

3. A tap for securing a pump rod against accidental displacement by gas pressure in a beer barrel or the like only by frictional engagement 100

between the tap and the rod, said tap having an opening through it for the rod and having an annular inwardly extending shoulder, said shoulder defining an opening of greater diameter than said rod to permit fluid passage past said shoulder, said shoulder being adapted as a seat for a rod washer, the face of said shoulder adjacent the 115 washer being inclined convergently toward said shoulder opening, a rod washer having its opposite faces uninterrupted and parallel and supported with one face in marginal contact with the shoulder and with the balance of said washer face 120 spaced from said shoulder face, said washer serving as the sole means for retaining said rod in position in said tap against tendency of barrel pressure to dislodge said rod, a follower engageable with said one end of said tap and having a 125

face in surface contact with the adjacent face of said washer substantially throughout the entire face of said washer, means engaging said tap for moving said follower against said washer to force the washer into gripping engagement with the inserted rod, the face of the washer adjacent the shoulder being forced out of parallelism with the other face of the washer and deflected toward the inclined face of the shoulder as said washer is compressed by said follower about said rod and against said shoulder, the deflection of said 140

named washer face making an obtuse angle with respect to the rod in a direction toward said shoulder and increasing the area of said washer face exposed to gas pressure in the barrel whereby gas pressure within the barrel enters against such deflected face of said washer to increase the holding effect of said washer against said rod. 145

4. A tap for securing a pump rod against accidental displacement by gas pressure in a beer 150

barrel or the like solely by frictional engagement, said tap having an opening through it for the rod and having an inwardly extending shoulder, said shoulder defining an opening of greater diameter than said rod to permit fluid passage past said shoulder, said shoulder being adapted as a seat for a rod washer, a rod washer supported on said shoulder with one face thereof adjacent the shoulder face, one of said faces being inclined convergently toward the rod in such manner that the major portion of the adjacent faces of said washer and shoulder are out of contact, a follower inserted in said tap and having a part for surface engagement with said washer, the contacting part of said follower conforming to the contacted face of said washer to afford surface engagement of said follower against said washer over substantially all of said washer face, means for moving said follower to compress said washer against its seat and against the rod for frictionally engaging the rod, the space between said shoulder and said rod admitting gas pressure against the face of the washer adjacent said shoulder thereby increasing the frictional engagement of said washer with said rod to prevent endwise displacement of the same with respect to the barrel.

5. A tap having a hollow interior to receive a pump rod, an annular shoulder within said interior having an opening for the rod which opening is of greater diameter than the rod to allow fluid passage past said shoulder, the face of said shoulder remote from the barrel end of said tap being inclined convergently toward said shoulder opening, a rod washer against said shoulder having marginal engagement therewith adjacent the

periphery of the greater diameter of said inclined face, the opposite faces of said washer being in parallelism, a follower cooperatively associated with said tap adjacent its outer end and having a flat part for surface engagement with the adjacent face of the washer, said follower being operable to compress said washer about the inserted rod and in a direction toward said shoulder, the compression of said washer by said follower distorting the washer in such manner as to deform the lower face thereof out of parallelism with its upper face and inclined such lower face with respect to the rod and toward the inclined face of said shoulder, said lower face of said washer making an obtuse angle with said rod in the direction toward said shoulder, the space between said shoulder and rod admitting barrel pressure past said shoulder and against the lower face of said washer to increase the holding effect of said washer against the rod, the rod being restrained against endwise movement solely by the gripping engagement thereof by said washer.

6. In a device of the class described, a vertically disposed member for surrounding a pipe, supporting means on said member, a packing on said supporting means and surrounding said pipe, means for compressing the packing to support the weight of the pipe and forming a high pressure seal, said packing when compressed having a part making an obtuse angle with said pipe, and said supporting means being so fashioned as to expose said packing part to fluid pressure to increase the holding engagement of said packing with said pipe.
